BRUSH STUFFING MACHINES

Emil Schneckenburger, Todtnau, Black Forest, Germany, assignor to Anton Zahoransky, Todtnau, Black Forest, Germany, a family corporation of Germany

Filed Sept. 27, 1961, Ser. No. 141,697

11 Claims. (Cl. 300—7)

This invention relates to brush stuffing machines. More particularly, it relates to an improved mechanism for feeding stuffing material to brushes without damaging such material.

Great difficulty exists in conventional brush machines in separating and withdrawing precise amounts of stuffing material, such as wires or bristles, from alternate compartments of a material holding container without disarranging and entangling the bristles. This operation is usually effected by alternately closing the lower opening of such compartments and swinging the container with its compartments relative to the withdrawal position of an oscillating gripper.

A device disposed at the bottom of the machine presses back the stuffing material into the compartment whenever it is arcuately swung into non-discharging position. The pressing device, however, tends to squeeze the material together in an irregular manner. Such irregularity is further augmented by different degrees of friction existing between the particles of the stuffing material per se and between the material and the compartment walls. These uneven frictional conditions inevitably lead to the gripper withdrawing uncontrolled quantities of bristles which are often in disorderly array. The result is poorly stuffed brush stock.

An object of the invention is to create an improved stuffing machine in which the above referred to difficulties are overcome by elimination of swinging containers.

Another object is to construct an improved machine wherein the working parts would be simplified for reliable operation and economical production of high quality brushes.

An important feature of the invention is a new type of container which shunts or shifts in a straight line either vertically as shown or horizontally between alternate positions on transverse bars. This construction allows a predetermined amount of stuffing material to be perpendicularly discharged from the separate compartments of the container and maintains the material under uniform pressure at an angle of 90° to the gripper.

A further feature is the parallel straight line displacement of respective compartments as a whole relative to each other. An orderly, even positioning of the stuffing material within the compartments is induced by this longitudinal movement which results in highly standardized stuffing operations.

As contemplated by the invention, the end compartment is fixed or integral with the container as it does not have to be raised in order to allow the gripper to freely pass underneath and withdraw stuffing material therefrom. Hence, in containers having just two compartments, only the compartment closest to the stuffing tool need be raised out of discharging position. When more than two compartments are used, all are longitudinally displaceable except the one which is furthest away from the tool. When the container shifts laterally in its reciprocating movement to a new withdrawing position, each displaceable compartment is simultaneously lifted and its discharge end automatically closed.

Each displaceable compartment is closed by suitable means when slid into inoperative position as it is being lifted, and is guided during its longitudinal sliding motion

2

by means of bars 19 and its adjoining compartment or compartments.

Advantageously, the lifting motion is effected by a pin attached to the displaceable compartment which rides in a uniquely shaped lateral guiding slot mounted on the machine base.

Further features and advantages of the invention will be apparent in the following detail description and the accompanying drawings which illustrate preferred embodiments of the invention, wherein

FIGURE 1 is a front elevation of a stuffing material container shown mounted on a portion of a brush stuffing machine with the first compartment in operative position;

FIGURE 2 is a sectional view of the container taken on line 2—2 of FIGURE 1;

FIGURE 3 is a front elevational view of the stuffing machine of FIGURE 1 showing the last compartment in operative position;

FIGURE 4 is a top plan view of the machine taken on line 4—4 of FIGURE 3; and

FIGURE 5 is a side elevational view of the stuffing machine container.

Referring now to the drawings, an angle iron 1 is fastened to the table or frame 17 of a combined brush punching and stuffing machine. A shuttle 3 is slidably mounted in a dove-tailed guide 2 which is attached to the frame as by angle 1. An intermediary member 4 rigidly connects the shuttle to a container box 18, and moves the container to and fro in the same co-axial direction as a combined gripper and bundle divider 11. The gripper, including picking needles disposed in a groove 32 of guide member 33 has a recess 20 which grasps the stuffing material 31 at a bundle taking position from separate compartments of the container and transports it from such position to a stuffing tool 21.

The container box illustrated in the drawings has two compartments 22 and 23. Compartment 22, the nearest to the stuffing tool, is illustrated as displaced vertically, relative to the end compartment 23, during the transverse movement of container 18.

Each compartment of the vertically mounted container extends between a centrally disposed bridge 5 and an outer sidewall 6. The container is open at the top to allow free access to filling the compartments with orderly arranged material, such as bunches of bristle and fiber, with which a brush may be alternately stuffed.

Compartments 22 and 23 each have a rear sheet 7, as shown in FIGURES 2 and 4. These sheets, disposed on either side of bridge 5, are individually fastened to a threaded spindle or set screw 8, see FIGURE 5. The position of the rear sheet may be controlled by adjusting a nut 9 mounted on each spindle to regulate the depth of each compartment in accordance with the length of stuffing material being used therein.

Grooves 27 are provided in bridge 5 and sidewalls 6 for guiding movement of removable slides 10 therein. Weights 12 of variable degree may be attached to the slides in order to exert a firm downward pressure against the top layer of the stuffing material. Compression springs 28 located in the lower portion of sidewalls 6 and bridge 5 carry bolts 29 which are attached to the lower ends thereof. The spring loaded bolts exert pressure on the picking needles 11 and/or on the needle counterpart or doctor 13 which in turn exerts pressure on the picking needles, see FIGS. 1, 3 and 5. This pressure on the needles is therefore received directly from the bolts or indirectly from the doctor.

The needle counterpart comprises a raised platform which rests upon but is not horizontally movable with the material picking needles. The counterpart or doctor is held in proper position by attachment to the stuffing

tool housing 34 as by a connector bar 35. This platform acts as an automatic closure for displaceable compartment 22 when the container is laterally slid toward the tool and away from the supply position or recess 20 in the material grasping sector. The lower horizontal portion of center rail or bridge 5 clears bristles from the picking mechanism during each change-over movement. When the first compartment is in raised position, the platform allows the bundle grasping needles 11 to pass freely beneath it and service the end compartment 23.

The vertical or longitudinal displacement of compartment 22 is effected by a pin 25 rigidly mounted thereon which rides in a two-plane, laterally disposed tangential slot 24, the upper level of which corresponds to the height of platform or stripper 13. As the container is pushed to the left, the pin is guided upward in the curved slot to its higher position and the compartment, frictionally slid onto the raised platform, is simultaneously closed at the bottom. The slot may be located in the upstanding side of an angular metal strip 14. The horizontal side of the strip is shown fastened to table 17 by means of a bolt or the like, see FIGURE 5.

Since the gripper needle 11 functions by repeated movements of equal length, the material taken by it is controlled by placing the proper compartment in the supply position. Therefore, while the needles always move to and fro for the same distance in the bristle taking and delivering operation, the containers are shunted from right to left relative to the bundle taking position of recess 20. For example, FIGURE 1 shows the container 18 shifted to the right so that compartment 23 is pushed beyond the taking sector and FIGURE 3 shows the container shifted to the left so that the gripper needle 11 can reach the end compartment.

The machine drive slides the container back and forth in guide 2 by means of exerting a push-pull action in the direction of the arrow 26 on spindle 16. The spindle is attached to a side of the container as by an internally threaded lug 15 and retaining nut 30.

It will be seen that this non-switching means of removing stuffing material from a container by slidably shunting its compartments in a co-axial line relative to the divider 11 passing directly below, entirely avoids the undesirable squeezing of such material as now exists in conventional stuffing machines. This is true regardless of the number of compartments in a non-swinging container.

As stated above, the invention may be used on containers with more than two compartments in which all would be similarly displaced except the end compartment, which is furthest away from the stuffing tool.

As stated above, the invention also applies to stuffing machines wherein the supply containers and the stuffing tool may be arranged horizontally instead of vertically. In both cases, guidance of the relative longitudinal displacement of the compartments in the container box is structurally feasible by means of overlapping, transversely disposed cross bars 19.

The forms of the invention here described and illustrated are presented merely as examples of how the invention may be embodied and applied. Other forms, embodiments and applications of the invention, coming within the proper scope of the appended claims, will, of course suggest themselves to those skilled in the art.

I claim:

1. In a brush stuffing machine having a frame, a stuffing tool, a guide means, a material gripping means and a transport means associated with said gripping means for moving stuffing material along said guide means from a supply position to said tool, a container adapted to supply said material in uniformly controlled amounts to said gripping means, said container comprising a fixed compartment and at least one movable compartment for receiving an evenly arranged supply of said material therein, movable means for sliding said container to and fro

above said guide means in a co-axial path therewith to alternately bring said fixed and movable compartments into and out of engagement with said gripping means, each said department being disposed perpendicular to said guide means to unobtrusively discharge said material at a 90° angle to said gripping means in said uniformly controlled amounts.

2. In a brush stuffing machine having a frame, a stuffing tool, material gripping means and transport means associated with said gripping means for moving a stuffing material from a supply position to said tool, a container disposed perpendicular to said gripping and transport means, said container provided with at least a first and second compartment for reception of said material therein, slideable means disposed on said frame for guiding said container in a straight line shunting parallel to the line of movement of said transport means, means disposed on said container for shunting said container in opposite directions to alternately bring said first and second compartment into engagement with said gripping means at said supply position, said first compartment being disposed alongside said second compartment and longitudinally displaceable relative thereto when the former is withdrawn from said supply position, said straight line shunting of said container maintaining both of said compartments at a 90° angle relative to said gripping and transport means.

3. A container according to claim 2 including displaceable means for said first compartment, said displaceable means comprising a member rigidly fixed to said frame having a tangential slot disposed therein and a pin fixedly secured to said first compartment, said pin being slidably mounted in said slot for lateral movement therein relative to said longitudinal displacement.

4. A container according to claim 2 wherein transversely overlapping bars are disposed at the outer end of said container, said bars forming a guide for longitudinal displacement of said first compartment.

5. A container according to claim 2 wherein said first compartment is provided with a rear panel, a threaded spindle is attached to said panel and adjustable means is disposed on said spindle to regulate the longitudinal displacement of said first compartment to accommodate various lengths of stuffing material when placed therein.

6. A container according to claim 2 wherein a stripper is mounted upon said frame, said stripper automatically closing the filled end of said first compartment relative to said transport means when said first compartment is in said withdrawn position.

7. In a brush stuffing machine having a frame, a stuffing tool, material gripping means and transport means associated with said gripping means for moving a stuffing material from a supply position to said tool, a container disposed perpendicular to said gripping and transport means, said container provided with at least a first and second compartment for reception of said material therein, slideable means disposed on said frame for guiding said container in a straight line shunting parallel to the line of movement of said transport means, means disposed on said container for shunting said container in opposite directions to alternately bring said first and second compartment into engagement with said gripping means at said supply position, said slideable means including a recessed member fixed to said frame, a shuttle slidably mounted in said member and rigidly attached to said container, said member and said shuttle cooperating to slidably support said container for operative association with said gripping means, said straight line shunting of said container maintaining both of said compartments at a 90° angle relative to said gripping and transport means.

8. In a brush stuffing machine having a frame, a stuffing tool, material gripping means and transport means associated with said gripping means for moving a stuffing material from a supply position to said tool, a container disposed perpendicular to said gripping and transport means, said container provided with at least a first and

second compartment for reception of said material therein, slideable means disposed on said frame for guiding said container in a straight line shunting parallel to the line of movement of said transport means, means disposed on said container for shunting said container in opposite directions to alternately bring said first and second compartment into engagement with said gripping means at said supply position, each of said compartments being provided with a rear panel, an outer longitudinal wall forming a side thereof, a common bridge separating said compartments and an open end for freely loading said material therein, and spring loaded elements disposed at the discharge end of said walls and said bridge, each of said elements exerting direct and indirect resilient pressure on said gripping means, said straight line shunting of said container maintaining both of said compartments at a 90° angle relative to said gripping and transport means.

9. A container according to claim 8 wherein each compartment is provided with a pair of longitudinal grooves disposed in said bridge and in said walls and wherein

15

5

a removable slide is mounted for guided movement within each pair of said grooves, each said slide serving to urge said material in its respective compartment toward the discharge end thereof into engagement with said gripping means.

10. A container according to claim 8, including a stripper, wherein at least one of said spring loaded elements bears upon said stripper to cause the latter to exert said indirect pressure on said gripping means.

11. A container according to claim 8 wherein said bridge is provided with a lower transverse end, said end adapted to clear excess bristles from said gripping means during each right angled displacement of said container relative to said gripping means.
